PATCH

Earl Bullis, Amsterdam, N. Y.

Application September 5, 1933, Serial No. 688,248

2 Claims. (Cl. 137—99)

This invention relates to an improved patch and is particularly adapted for use in mending pots, pans, hot water bottles and the like.

One object of the invention is to provide a patch which will be so formed that the sealing disk employed therewith will uniformly engage the surface to be patched so that danger of leakage at a point or points will be largely eliminated.

Another object of the invention is to provide a patch of such construction that the sealing disk will be largely protected and prevented from cracking and chipping away.

A further object of the invention is to provide a device of this character embodying a shank which is secured to the head employed in such a manner that said shank and head will be mounted as a unit, and will be effectually limited against separation from each other.

A further object of the invention is to provide a patch which will be characterized by the utmost simplicity and greatest efficiency so that, after mounting in place, it will effectually close a leak and will not require further attention after installation.

And a still further object of the invention is to provide a device of this character wherein the upper end of the shank may be embedded in the head so that a smooth upper surface for the head will be accorded.

Other and incidental objects of the invention, not hereinabove discussed, will be apparent as the description of the invention proceeds.

My invention is illustrated in the accompanying drawing wherein Figure 1 is a fragmentary vertical sectional view of my patch in the process of construction and showing the shank extending through the head,

Fig. 2 is a vertical sectional view showing the device with the shank in position on the head during the process of upsetting the ribs carried on said shank,

Fig. 3 is a vertical sectional view of my completed patch and showing the same in position on a surface to be patched,

Fig. 4 is a vertical sectional view showing a slightly modified form of my invention,

Fig. 5 is a side elevational view showing the stud employed before being upset upon the head,

Fig. 6 is a bottom plan view of the stud,

Fig. 7 is a vertical sectional view showing a further modification of the invention,

Fig. 8 is a top plan view of the device as shown in Fig. 7, and

Fig. 9 is a fragmentary vertical sectional view

showing a still further modified form of the invention.

Referring now more particularly to the accompanying drawing wherein like numerals of reference designate like parts throughout the several views, the numeral 1 indicates the head of my improved patch which is preferably formed of a strong aluminum alloy and which is concavo-convex in shape, the circumferential edge of said head being straightened, as indicated at 2. The head is apertured and pressed inwardly to define an annular seat 3. It is emphasized that the head of the patch is made of an alloy of aluminum instead of tin plate or other rustable metal, so that danger of rusting and ruining of the patch will be eliminated. The head may also be stamped from a single sheet of metal and formed into the desired shape with the seat 3 formed therein. This may be done by a single stamping operation, if so desired, so that the heads may be stamped out in great quantities at a minimum cost.

Carried by the head 1 is a stud which is indicated in general by the numeral 4. The stud is provided with an enlarged top portion 5 which is adapted to rest in the seat 3. The stud also includes a shank having an enlarged upper portion 6 and a reduced lower portion 7, said lower portion being adapted for external threading.

As shown in Fig. 2 of the drawing, after the stud has been passed through the opening in the head and the portion 5 rested in the seat 3, a suitable tool, such as is shown at 8, is fitted about the end of the shank and is driven upwardly for peeling back the enlarged portion 6 to lie against the undersurface of the head so that the stud will be firmly upset in position on the head. The stud is made of aluminum as well as is the head so that there will be no danger of electrolytic action such as might be present if different kinds of metals were employed. By forming the stud of aluminum, it is, of course, possible to eliminate rust.

The stud is preferably made from heavy wire and is formed in a heading machine by the well-known upset process. This stud may, of course, like the head, be produced in large quantities at a very cheap figure. The reduced portion 7 of the shank is threaded, as indicated at 9 in Fig. 3 of the drawing and said threaded portion is adapted to receive a securing nut 10 which overlies a washer 11, which washer bears against the inner face of the surface to be patched, a portion of such a surface being shown at 12 in Fig. 3. It

should, of course, be understood that the portion 7 is passed through the leak, said leak being enlarged to permit such passage, and then the nut 10 is screwed into place, after the washer has 5 been placed in its proper position.

While it has been shown that the head is to be formed of circular frusto-conical shape, it should be understood that if it is desired to mend irregular surfaces, the head of the patch may be bent 10 to conform to the shape of the surface to be mended.

Carried by the head 1, at its lower surface, is a sealing disk 13 which is formed of cork, soft rubber or any other suitable sealing material. The 15 sealing disk is of a diameter slightly greater than the diameter of the head so that its outer circumferential edge projects beyond the circumferential edge of the head. The disk 13 is provided with a relatively large central opening 14 20 which is adapted to receive the inwardly pressed portion defining the seat 3. It will be understood that this inwardly pressed portion cooperates with the opening 14 for retaining the sealing disk in proper position on the head. After the patch 25 has been placed in position and the nut has been placed on the threaded portion 8, said nut is tightened for closely and uniformly clamping the sealing disk about the leak to be mended. It will be seen, therefore, that the leak will be effectually sealed so that further leakage therefrom will be an impossibility.

My improved patch, after being placed in position, will last throughout the remainder of the life of the utensil to which it is attached and will, 35 in all probability, require no further attention. Should, however, the device become loose, it is only necessary to tighten on the nut 10, when the patch will again be firmly anchored in place. The flat portion 2 of the head will firmly engage the 40 outer edge of the sealing disk, without mutilating said surface, and will effectually retain the sealing disk in sealing position throughout the length of the entire circumferential edge of the head. It should be understood that, while I have 45 shown the head and shank of the preferred form of my device as being in two pieces, said head and shank may be formed from a single piece of material.

Referring now more particularly to the modification of my invention, as shown in Fig. 4, I 50 employ a head 15 which is of substantially identical construction with the head 1. Mounted on the head 15 is a stud 16 having an externally threaded shank 17 and a flattened enlarged upper portion 18 which projects above the surface of the head 15. The shank is shown in elevation in Fig. 5 of the drawing and is provided with ribs 19 which are upset against the lower surface of the head by a tool similar to the tool shown at 8 55 so that the head and stud will be firmly mounted as a unit. A sealing disk, similar to the disk shown at 13 in the preferred form, is employed with this modified form and a nut is, of course,

screwed upon the lower end of the shank 17. The operation of the device is similar to that of the preferred form but this construction is advantageous inasmuch as cheapness in manufacture is accentuated.

Referring now to the modification of my invention as shown in Figs. 7 and 8 of the drawing, I employ a substantially frusto-conical head 19 having a flat marginal edge 20. The head is formed of the same material as is employed in connection with the preferred form of the invention. Formed in the head 19 are radially extending upwardly pressed portions defining ribs 21 which are gradually reduced in height toward the edge of the head so that said head will be 15 retained against undue spreading movement. A stud 22 having an externally threaded shank 23 is carried by the head and is adapted to function in a manner identical with that of the preferred form. This form of the invention will serve the 20 same purpose, and will operate in a manner identical with the preferred form of the invention, aside from the above-mentioned ribs, which will, as stated, prevent rotative movement of the sealing disk carried beneath the head.

Referring now to the modification of the invention as shown in Figure 9 of the drawing, I employ a head 24 which is provided with an axial socket 25. The socket is adapted to receive the upper end portion 26 of a stud 27, and as will be 30 observed, the upper surface of the stud is adapted to lie in the same plane with the head 24. It will be seen that a smooth upper surface for the head will be provided.

In view of the foregoing description, it is 35 thought that the construction and operation of my device will be clearly understood. Further description thereof will be unnecessary.

Having thus described the invention, I claim:

1. A device of the character described comprising a concavo-convex disk having its outer face convexed and its inner face concaved, said disk being formed with a center opening and about the opening being depressed to form a countersunk seat having a marginal wall and an inwardly extending annular flange bordering the opening, a stud having a shank extending through the opening and a head at the outer end of the shank snugly received in said seat with its marginal edge face contacting with the marginal wall of the seat, said shank having a thickened portion engaged through the opening and upset to form a collar engaging the under face of the seat flange and clamping the flange against the head to firmly unite the disk and stud, and securing means adjustably carried by said stud.

2. The structure of claim 1 and a sealing pad fitting against the inner face of said disk, said pad conforming to the contour of said disk and fitting snugly about the marginal wall of the countersunk seat of the disk to prevent movement of the pad radially of the disk.

EARL BULLIS. [L.S.]
